United States Patent

Des. 239,779
Patented May 4, 1976

239,779

TARGET BOARD

Allan M. Elfman, 219 E. 83rd St.,
New York, N.Y. 10028

Filed Nov. 4, 1974, Ser. No. 520,738

Term of patent 14 years

Int. Cl. D21—01

U.S. Cl. D34—5 PP

FIG. 1

FIG. 2

FIG. 3

FIG. 4

FIG. 5

FIG. 1 is a front elevation of a target board embodying my new design;

FIG. 2 is a top plan view;

FIG. 3 is a bottom plan view;

FIG. 4 is a side elevation view; and

FIG. 5 is a rear elevation of the target board.

I claim:

The ornamental design for a target board, as shown.
